UNITED STATES PATENT OFFICE.

LOUISA WOHLTMAN, OF NEW YORK, N. Y.

DESIGN FOR A SOUVENIR-PLATE.

SPECIFICATION forming part of Design No. 35,410, dated December 10, 1901.

Application filed November 5, 1901. Serial No. 81,275. Term of patent 14 years.

To all whom it may concern:

Be it known that I, LOUISA WOHLTMAN, a citizen of the United States, residing in the borough of Manhattan, city of New York, county of New York, and State of New York, have invented and produced a new and original Design for a Souvenir-Plate, of which the following is a specification, reference being had to the accompanying drawing, forming part thereof.

This invention relates to designs for souvenir-plates.

The accompanying drawing shows a front view of my new design.

As shown in the drawing, the leading or material feature of my design consists in a center disk A, having a raised circumferential rim B, on which are raised beads C. Above the center disk A is arranged a cross-bar of an anchor D with an eye E. Upon this upper part of the anchor are two links F, and on said bar D are four bands G. Below the center disk A is the lower part of an anchor H, on which are three links I. Around

the center disk A is a horseshoe J, at the top 25 of which is a raised toe K, and at the bottom of said horseshoe are raised heels L. In each side of the horseshoe J is a groove M, extending from the toe K down each side of said horseshoe, and in each of said grooves M are 30 four depressions N to represent the holes for the nails of the said horseshoe J. Immediately around the rim B and on the said horseshoe J is ornamental raised work O, and on said horseshoe J is a suitable place for any 35 desirable words P.

Having described my invention, what I claim as new, and desire to secure by Letters Patent, is—

The design for a souvenir-plate as herein 40 shown and described.

In testimony whereof I have signed my name to this specification in the presence of two subscribing witnesses.

LOUISA WOHLTMAN.
